(57) **CLAIM**

The ornamental design for a hunting call, as shown and described.

DESCRIPTION

FIG. 1 is a perspective view of a hunting call showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

In the drawings, the broken line showing of a pattern on the body of the design depicts environmental subject matter and forms no part of the claim.
